LOCK

Josef Hammarle, San Francisco, Calif.

Application December 30, 1935, Serial No. 56,780

2 Claims. (Cl. 70—118)

This invention relates to improvements in locks, and has particular reference to a lock for doors, whereby the door is secured top and bottom as well as at the side.

5 A further object is to produce a device which prevents the customary bolt from being operated when the top and bottom pins are projected.

A further object is to produce a device which may be installed in the ordinary door without 10 materially altering its construction and one which may be economically manufactured.

Other objects and advantages will be apparent during the course of the following description.

15 In accompanying drawings forming a part of this specification and in which like numerals are employed to designate like parts throughout the same,

Fig. 1 is a front elevation of a door having my 20 invention applied thereto;

Fig. 2 is a side elevation of the lock with the plate removed and showing the top and bottom pin sockets in cross section;

Fig. 3 is a side elevation of the lock showing 25 the parts in locked position;

Fig. 4 is a cross sectional view taken on the line 4—4 of Fig. 3;

Fig. 5 is a side elevation of the slider;

Fig. 6 is a perspective view of the pusher; and 30 Fig. 7 is a plan view of the slider.

The ordinary door lock merely projects a sliding bolt into a socket of the casing of a door, which type of lock is very easy to break out. I have, therefore, devised a lock which not only 35 slides a bolt into the side casing of a door but also projects a pair of pins upwardly and downwardly into the lintel and sill of the door.

In the accompanying drawings wherein for the 40 purpose of illustration is shown a preferred embodiment of my invention, the numeral 5 designates the ordinary door having a jamb 6, lintel 7 and sill 8. At 9 I have shown the casing of a lock which may be set upon the door or mortised thereinto. Extending in opposite directions 45 from the casing 9 are guide tubes 11 and 12 through which rods 13 and 14, respectively, slide. These rods terminate in pins 16 and 17 which enter sockets 18 and 19, respectively, and are projected and retracted in a manner later to be 50 described.

L-shaped members 21 and 22 are connected to the rods 13 and 14, respectively. Each of the L-shaped members are provided with teeth which engage a gear 23 mounted upon a key shaft 24, which shaft may be provided with a handle 26

upon the inside of the door and with a transverse kerf at its outer end for the reception of a key 27 for turning said shaft from the outside of the door as shown in dotted lines in Fig. 4. It will thus be noted that the gear 23, members 21 and 22, the rods 13 and 14, and the latch bolt may be unlocked from the outside of the door as is apparent from the foregoing description. The L-shaped member 22 carries a projection 28, which when in the position of Fig. 3 10 prevents the slider 29 from moving along its track 31. This slider has attached thereto the bolt 32 and is actuated against the tension of springs 33 by a rollback 34 mounted upon the squared shaft 36. This squared shaft may be rotated 15 through the medium of the customary door knob 37 when the parts are in the position shown in Fig. 2 and the projection 28 lies out of the plane of movement of the slider and consequently the bolt 32 may be actuated.

20 The manner of locking a door with my arrangement is that the door is closed in the customary manner and then the key 27 is employed to rotate the gear 23, thus causing the rods 13 and 14 to move their pins 16 and 17 into the 25 sockets at the top and bottom of the door opening. This act will also prevent the bolt 32 from being retracted until these pins have been withdrawn from their sockets.

It will thus be seen that I have produced a 30 device which will accomplish all the objects above set forth.

It is to be understood that the form of my invention herewith shown and described is to be taken as a preferred example of the same and 35 that various changes relative to the material, size, shape and arrangement of parts may be resorted to without departing from the spirit of the invention or the scope of the subjoined claims.

40 Having thus described my invention, I claim:—

1. In a device of the class described, a casing, tubular guides secured to said casing and extending in opposite directions relative to each other, locking rods movable in each of said 45 guides, L-shaped rack members secured to the inner ends of the rods, a gear positioned between said L-shaped members and having toothed engagement therewith, one of said L-shaped members having a projection secured 50 thereto, a slider mounted in said casing provided with a latching bolt, a roll-back member cooperating with said slider, whereby when said projection is projected it engages with said slider and latches said bolt and when moved inwardly 55

releases the same, and key operated means for rotating said gear.

2. In a device of the class described, a casting, oppositely disposed tubular guides secured to said casing, locking rods capable of being moved outwardly in said tubular guides, L-shaped rack members mounted on the inner ends of said rods, an actuating gear positioned between said L-shaped members and having toothed engagement therewith, a projection carried by one of said L-shaped members, a latch spindle and a latching bolt cooperating with said latch spindle,

a spring controlled slider carried by said bolt and a roll-back mounted on said spindle and cooperating with said slider, whereby when said projection is projected it engages said slider and locks said bolt against movement, and when moved inwardly it releases said bolt, and a key operated means associated with said gear, whereby said L-shaped members and rods may be operated to lock said bolt by means of said projection. 5 10

JOSEF HAMMARLÉ.
